UNITED STATES PATENT OFFICE.

ALEXANDER L. WARD, OF NEW YORK, N. Y.

LOCKING DEVICE FOR COLLAPSIBLE CONTAINERS.

1,380,875.

Specification of Letters Patent. Patented June 7, 1921.

Application filed August 5, 1918. Serial No. 248,312.

To all whom it may concern:

Be it known that I, ALEXANDER L. WARD, a citizen of the United States, residing in the borough of Manhattan, city, county, and 5 State of New York, have invented certain new and useful Improvements in Locking Devices for Collapsible Containers, of which the following is a specification.

My invention relates to locking or securing devices for fastening the covers of knock-down packing and shipping boxes, and the like, upon the upstanding sides, in which position the sides and ends are sustained and the container rigidly assembled. My invention is particularly applicable to containers of the character described and claimed in my Patent Number 1,273,430, dated July 23, 1918, and in application Serial No. 163,542, filed April 21, 1917, in both of which the cover 10 is provided at its edges with portions of inverted U-section or grooves, in which the upper edges of the side and end members extend when the container is assembled. My present invention provides improved locking 15 devices which are slidably extended from the body of the cover through the outer depending flanges of the cover and the vertical members which extend into the inverted U 20 of the cover, preferably adjacent the corners and positions intermediate the covers, in which positions sealing wires may be extended through holes in the cover and the locking devices. The object of my invention is to provide improved details of construction and combinations of parts in such 25 devices, as will be hereinafter more fully described.

In order that my invention may be more fully understood, attention is hereby directed 30 to the accompanying drawings forming part of this application and illustrating certain embodiments of my invention. In the drawings, Figure 1 represents a partial top plan view of a container carrying end and intermediate locking devices, Figs. 2, 3 and 4 are sections taken on lines 2-2, 3-3 and 4-4, respectively, of Fig. 1. Fig. 5 is a partial top plan view of a different form of container, carrying end and intermediate 45 locking devices, Figs. 6 and 7 are enlarged 50

sections taken respectively on lines 6-6 and 7-7 of Fig. 5, Fig. 8 is a partial front elevation, looking in the direction of the line 8-8 in Fig. 5, Figs. 9 and 10 are sections taken respectively on lines 9-9 and 10-10 55 of Fig. 8, and Fig. 11 is a bottom plan view of the parts shown in Fig. 7.

Referring first to Figs. 1 to 4 of the drawings, the cover section of the container is formed of a horizontal body portion 1, and 60 integral edge portions bent upwardly as at 2, thence outwardly at 3 and downwardly at 4, the cover being formed of a sheet of metal, in this construction. At the bottom of the outer flange 4 the metal may be bent 65 inwardly and then upwardly, at 5, about the lower end of an angle-iron 6, which extends all around the cover. The upper edges of the side sections 7 and the end sections 8 extend into the groove thus formed between the flanges 5 and 4 and the vertical leg of angle 6 on one side, and the flange 2 of the cover on the other side, the side and end sections preferably being formed as described in my said Patent No. 1,205,418, with 70 vertical edge flanges, the edge flanges of the end sections resting against the inner surfaces of the side sections, adjacent the corners, and the vertical edge flanges of the side sections resting against the outer surfaces of 75 the end sections, adjacent the corners.

Bolts 9, 9 are slidably mounted on the top surface of the cover adjacent the corners, and are adapted to be shot through aligned 80 openings in the vertical flanges 2 and 4 of the cover, the angle member reinforcement 6, and the interposed side members and vertical edge flanges on the end members to lock 85 the parts together. Each bolt 9 is parallel to, and slides in contact with, an inner vertical flange 2 of the cover, as shown in Fig. 3. Each bolt is held in position and guided by a cover plate 10, which may be fastened 90 at one end to the cover section 1, as shown at 11, and bent upwardly to extend over 95 the bolt and into contact with the vertical flange 2, as shown. Each bolt 9 is preferably formed with an angular extension 12 at its inner end, to form an operating handle, and with an extension 13, parallel to 12, at 100

a point on the bolt forward of extension 12. The metal of the cover plate 10 is bent down, as shown at 14, at its side edge distant from the side member 7 of the container, in line 5 with extensions 12 and 13 of the bolt, to form a stop to coact with extension 13 to prevent the bolt being entirely removed from its cover plate, extension 13 sliding in contact with the vertical flange 15 of the cover 10 plate. Extension 13 also abuts against the adjacent flange 2 at the side of the cover, when the bolt is shot, to accurately position it in that position.

When each bolt 9 is shot, one end of a 15 sealing wire 16 may be passed down through an opening 17 in the top flange 3 and the horizontal leg of angle 6, and the other end of the wire is passed down through an opening 18 in the top flange 3 and angle 6, adjacent to opening 17. This end of the wire passes through an opening in bolt 9 which alines with opening 18 when the bolt is in locking position, as shown, both ends of the wire passing down through the space 20 between the vertical leg of angle 6 and the side section 7 of the box or container, and being secured together by an appropriate seal.

A bolt 19 is preferably used at one or 30 more points intermediate the ends of the box, at each side thereof, to hold the cover firmly down on the side members 7, these bolts being, of course, more necessary as the length of the box increases. Bolts 19 35 may be, and preferably are, flat pieces of metal which slide into position over the top surface of the body 1 of the cover member of the box, and through alining openings in flange 2, side member 7, the vertical leg of 40 angle 6 and the outer flange 4 of the cover. Each bolt 19 may be formed with an enlarged inner end 20 which is adapted to abut against the flange 2 when the bolt is shot, head 20 being preferably formed with 45 a groove 21 in its edge, so that the same may be readily grasped between a thumb and forefinger. A sealing wire may be passed through opening 17' in top flange 3 and the top flange of angle 6, and through opening 50 18' in top flange 3, angle 6, and bolt 19, and the ends sealed, in the same manner as described above in connection with bolts 9.

Referring now to Figs. 5 to 11 of the 55 drawings, improved fastening devices are shown for a box of the character described in my application Patent Number 1,273,430, referred to, in which the box or container is formed of sections of composition board, or the like, with flanges required for holding 60 and interlocking the parts in position formed of sheet metal secured to edges of the sections. The cover section comprises composition board 22 or the like, having an edge flange formed to extend about the 65 same, something like an inverted U, by se-

curing strips of sheet metal 23 to the upper surface of member 22 adjacent its edges. These strips extend outwardly past the edge in a horizontal flange, as shown at 24, the metal then being bent downwardly, as 70 shown at 25, and again upwardly, as at 26. Other strips, as shown at 27, are secured to the under side of member 22, adjacent the edge, and extend upwardly, as at 28, alongside the edge, then horizontally outwardly, 75 as at 29, in contact with the under side of flange 24, and then downwardly, as at 30, between flanges 25 and 26, flanges 25, 30 and 26 being pressed together. The side members of the container, such as 31, may 80 also be formed of composition board, with vertical side flanges 31' formed of metal strips secured to the outer faces of the members adjacent their vertical edges and bent inwardly past said edges. The end sections 85 (not shown) may be formed in the same way as the side sections, but with their metallic vertical side flanges 31² secured to the inner faces of the composition board. The container is set up with the end sections 90 inside the side sections, as in the form of my device described above in connection with Figs. 1 to 4. The upper edges of the side and end sections are adapted, when set up, to extend into the spaces between flanges 95 26 and 30 of the cover on one side, and flange 28, on the other, as shown in Fig. 9. The construction described is set forth in detail in my application Serial No. 163,542 referred to, but it is, of course, to be understood that the locking devices to be described are not limited strictly in their applicability to the exact form of cover and container described.

With containers of the general form just 105 described, locking bolts are used at the ends of the sides, and at intermediate points on the sides, as in the case of the first form of my invention described. One of the end bolts, of which four may be used, is shown 110 at 32 in Figs. 7 and 11. Each of these bolts is slidably mounted in a recess 33 in the composition board of the cover, between the upper and lower metallic flanges 23 and 27 adjacent the edge of the cover, and between an end flange 28 and the vertical edge of the recess in the board parallel to the end flange 28. The bolt may be of rectangular section, as shown in Fig. 6, or other desired section, with a front portion 115 34 offset downwardly from the body of the bolt, sufficiently to extend under the flange 28.

When the bolt is shot, and the cover is on the container, as shown in Fig. 7, the portion 34 of the bolt extends through alined openings in the side member 31, the side flange 31² of the adjacent end section, and the flanges 26, 30 and 25 of the cover, with the end of the body portion 32 of the bolt 120 125 130

contacting against the flange 28 of the cover as a stop. The bolt is preferably latched in forward and back positions by means of a leaf of spring metal 35 which may be secured to the under flange 27 of the cover, and is provided with an upwardly-curved bead 36. The latter is adapted to coact with a notch 37 at the rear end of the bolt to hold the latter in shot position, and to spring into a notch 38 in the bottom surface of the bolt, to latch the latter in retracted position. The flange 27 is cut away, as shown at 39, to permit the forward offset portion 34 of the bolt to move back to retracted position. The leaf spring 35, which may be the same width as the bolt, may be mounted in position under the bolt and over flange 27, with one end of the spring inserted through a slit at 40 in flange 27, and bent forwardly, and the other end of the spring bent around the edge of flange 27 adjacent the cut-out 39 thereof, as shown at 41. The flange 27 is also cut away for a sufficient distance under the bead 36 to permit the latter to spring downwardly, to ride under the bolt.

The upper surface of the bolt is provided with a notch 42, and the top flange 23 of the cover is cut away for a distance, as shown at 43, above the bolt, to give access to the notch, to move the bolt back and forth by means of a nail, or the like. Holes 44, 45 are provided through the top flanges 24, 29 of the cover, and through the bolt, in alignment with hole 44 when the bolt is shot, for the passage of a sealing wire 46, as explained in connection with the form of devices described in connection with Figs. 1 to 4 of the drawings.

Bolts are also provided at intermediate points along the sides of the cover, as shown in Figs. 8, 9 and 10. Each such bolt 47 preferably takes the form of a thin flat plate having a rear stem-like extension 48, the bolt being adapted to be slid into position from the outside, through aligned openings in the flanges 25 and 30 of the cover, and the side member 31. The stem 48 also extends through a suitable opening in flange 28 and into the board 22 of the cover, the rear edge of the body portion 47 abutting against flange 28 as a stop. Bolt 47 is provided with a suitably placed opening 49, and the top flanges 24, 29 of the cover with an aligned opening, 50, when the bolt is shot, through which, and the opening 51 in the top flanges of the cover, a sealing wire 52 may be passed, as previously explained, the wire passing through the space between the outer depending flanges of the cover and the side member 31, as in the cases of the other forms of bolts described. A reinforcing metallic plate 53 may be secured on the outer face of side member 31, through which extends the opening for bolt 47.

It will be understood that my invention is not limited strictly to the exact details of construction described. In the claims, references to ends and sides and the like, will be understood to be relative, since the container may be square or elongated, etc., and the bolts may extend through "end" sections, if desired, instead of, or in addition to, bolts through the "side" sections.

What I claim is:—

1. In a container, the combination of vertical sections, a cover section having edge flanges bent to form an inverted U-shape thereabout, into which the upper edges of the vertical sections extend when the container is assembled, horizontal bolts adjacent the corners of the cover section, mounted to slide on the cover section against the inner vertical edge flanges of the ends and to extend through openings in the side sections and outer side vertical cover flanges in alignment therewith, flanged cover plates extending transversely across said bolts, having upwardly extending shoulders at one side and abutting against said inner vertical edge flanges at the other side, said bolts having side offset portions thereon adapted to slidably engage said shoulders and to abut against the inner vertical side flanges of the cover, to stop the bolts in shot position.

2. In a container, the combination of vertical sections, a cover section having edge flanges bent to form an inverted U-shape thereabout, into which the upper edges of the vertical sections extend when the container is assembled, flat horizontal bolts at points intermediate the corners of the cover section, mounted to slide on the upper surface of the cover section through aligned openings in the inner and outer vertical edge flanges of the cover section, and the interposed side section, said bolts having holes therethrough and shoulders on the rear portions thereof adapted to contact against the inner vertical edge flanges of the cover section when the bolts are shot, the top edge flanges of the cover section having vertical holes therethrough, and sealing wires extending through said holes in the top flanges and the bolts and through the space between said outer cover flanges and said side sections.

3. In a container, the combination of vertical sections, a cover section having edge flanges bent to form an inverted U-shape thereabout, into which the upper edges of the vertical sections extend when the container is assembled, horizontal bolts adjacent the corners of the cover section, mounted to slide on the cover alongside the inner vertical edge flanges of the ends and to extend through openings in the side sections and outer side vertical cover flanges in alignment therewith, and cover plates extending

transversely across said bolts and having inner end flanges, said bolts having offset portions positioned between said cover plate flanges and the inner vertical side flanges 5 of the cover, to keep said bolts within the cover plates and to stop them in shot position, said bolts having handle portions extending beyond said cover plate end flanges.

This specification signed and witnessed this 18th day of July, 1918.

ALEXANDER L. WARD.

Witnesses:

I. McINTOSH,
DYER SMITH.

It is hereby certified that in Letters Patent No. 1,380,875, granted June 7, 1921, upon the application of Alexander L. Ward, of New York, N. Y., for an improvement in "Locking Devices for Collapsible Containers," errors appear in the printed specification requiring correction as follows: Page 1, strike out lines 17-19 and insert instead *Patent Number 1,205,418, dated November 21, 1916, and my Patent Number 1,273,430, dated July 23, 1918, and in both of which the cover; page 2, line 56, strike out the word "application"; and that the said Letters Patent should be read with these corrections therein that the same may conform to the record of the case in the Patent Office.*

Signed and sealed this 2d day of August, A. D., 1921.

[SEAL.]

KARL FENNING,

Acting Commissioner of Patents.
